UNITED STATES PATENT OFFICE

2,196,207

MANUFACTURE OF METAL WRITING PENS

Albert G. Frost, Philadelphia, Pa., assignor to The Esterbrook Steel Pen Manufacturing Company, Camden, N. J., a corporation of New Jersey

Application July 1, 1935, Serial No. 29,262
Renewed December 16, 1938

5 Claims. (Cl. 113—32)

My invention relates to the manufacture of metal writing pens or pen points, and comprises certain improvements in the method of making rounded end or, as they are sometimes called, 5 "ball-pointed" pens.

My invention comprises a sequence of novel steps constituting an improved method of transforming flat metal blanks into perfect pens or pen points of the rounded or "ball-pointed" type.

10 Pens or pen points may be made in accordance with my invention from various metals—stainless steel, brass, and the like—and the important feature of my improved method is the series of steps which result in the production of pens or pen 15 points of the type noted with a smooth writing surface and avoid the losses hitherto common in all previous methods of making pens or pen points with protuberant writing surfaces of the rounded end or "ball-pointed" type.

15 These and other features of my invention are more fully set forth hereinafter; reference being had to the accompanying drawing, more or less diagrammatic in character, in which:

Figure 1 is a plan view of one form of metal blank which may be employed in the production of pens or pen points in accordance with my invention.

20 Figs. 2 and 3 are fragmentary views on a larger scale, illustrating successive stages of the blank in the production of pens or pen points in accordance with my invention.

Fig. 4 is a view in longitudinal elevation, partly in section, showing one manner of indenting the writing tip end of the blank in connection with 25 the formation of the rounded or "ball" point.

25 Figs. 5, 6, 7, and 8 are fragmentary views of the writing tip end of pen or pen point blanks, showing modified forms of indentations and, in the case of Fig. 8, a modified tip, within the scope 30 of my invention.

Fig. 9 is a longitudinal sectional view on the line IX—IX, Fig. 2.

Fig. 10 is a similar view, taken on the line X—X, Fig. 3.

Fig. 11 is a front elevation of the writing tip end of the blank after formation of the indentation to produce the protuberance, looking in the direction of the arrow *a*, Fig. 2.

Fig. 12 is an enlarged sectional view on the line XII—XII, Fig. 3.

Fig. 13 is an enlarged sectional view on the same plane as Fig. 12, illustrating a modified form of indentation.

Fig. 14 is a fragmentary view in plan of the

nibs and writing tip end of a finished pen or pen point.

Fig. 15 is a front elevation of the writing tip end of the finished pen or pen point.

Fig. 16 is a sectional view on an enlarged scale 5 taken on the line XVI—XVI, Fig. 14.

Fig. 17 is a sectional view similar to Fig. 16, illustrating the finished form of the writing tip end of the pen or pen point having a protuberance 10 of the type illustrated in Fig. 13, and

Figs. 18 and 19 are fragmentary views in plan and elevation respectively, illustrating another form of writing tip end which may be produced in accordance with my invention.

One practice, heretofore followed in the manufacture of round or "ball-pointed" pens or pen points, is to "form" or "raise" the blank to final pen or pen point form and, after the slitting operation, to provide the nibs, which slitting operation might precede or follow the "forming" 15 or "raising" step, to recess the writing tip end of said nibs to produce the protuberance constituting the rounded or "ball" point. The recessing of the nibs to form such protuberance following the slitting operation, however, has a 20 tendency to distort or crush the ends of the nibs and cause portions of the protuberance designed to contact with the paper to spread, with the result that smoothness of the writing tip end is 25 destroyed, and many imperfect pens or pen points 30 result. Attempts have been made, in the production of pens or pen points of this type, to effect the desired recessing of the writing tip end before the usual slitting operation, but this action of slitting the raised pen or pen points following 35 the formation of the protuberance also results in the spreading of the ends of the nibs, as well as distortion of the protuberant portion together with roughening of the surface of the latter at 40 the writing tip end of the pen or pen point.

In carrying out my invention, the blanks for the pens or pen points are formed in the usual manner by stamping the same from metal stock 45 of the desired character; a blank of one form being shown at 20, Fig. 1. These blanks are pro-

vided at the tapered portion from which the nibs are subsequently formed, with a relatively broad end 21, which may be rounded as indicated at 21^a for the formation of the writing tip end of the finished pen or pen point, or of other shape. 50

The blanking operation may leave sharp, relatively rough edges at the margins of the blank at one face of the same, while the opposite surface may have rounded edges, due to the natural draw in the blanking operation.

After the blanking step, the blanks are pierced in the usual manner, as indicated at 22, Fig. 3. The shape of the pierce hole is a matter of indifference, and in the present instance, it is conveniently shown as round.

Following the preceding operation, the blanks are marked with the maker's name, style, number, or other indicia, etc., and then the writing tip end of the blank is recessed at 23 on the up-10 per side by a suitable tool; that illustrated at 24, for instance, such recessing producing a protuberance 25 on the underside of the writing tip end of the blank.

The recess formed in the upper side of the 15 blank and reproduced on the underside thereof in the form of a protuberance may be round or truly circular, as shown in Figs. 2 and 3; it may be oval and lie longitudinally or transversely of the writing tip end, as shown in Figs. 5 and 6, 20 respectively; or it may be of pear shape with the broader dimension thereof disposed toward the pierce hole 22, as shown in Fig. 7. It will be understood that the modified recessing, indicated in Figs. 5, 6, and 7, will provide variations in the form of the protuberances.

After the recessing operation, the blank is cut to provide the nibs of the finished pen or pen point; such cut, indicated at 26, being straight through the longitudinal axis of the blank from 30 the writing tip end to the pierce hole, as illustrated in Fig. 4. While this cut may be made in a number of ways, I prefer to effect it by a sawing operation which produces a clean-cut slot 26 of uniform width throughout its length 35 and without distorting in any way the nibs or the protuberant portion formed by the recessing operation at the writing tip end of the blank. This sawing operation provides the separate nibs 27 flanking the slot 26, and the width of this slot 40 may affect, in some measure, the width of the writing point end of the finished pen or pen point. In all instances, the sawing operation provides a definite gap between the nib ends at the writing tip end of the blank.

45 The blanks from the sawing step, and still flat, are then placed in the usual tumbling barrel for the purpose of smoothing the sharp or rough edges of the same, rounding corners, and the like. This may be a "wet scouring", and this 50 operation has the effect of smoothing the blanks. By "wet scouring" the blank in the flat state following the sawing operation, all of the rough or sharp edges are removed—particularly the corners of the protuberances at the writing tip 55 portion of the same. When the blank thus prepared is "raised" into pen or pen point form, the nibs of the same are automatically brought into the desired relative position, and the relatively contacting surfaces of the nib ends looking toward the writing tip end of the pen or pen point 60 are in exact parallelism and normal to the plane of the top surface of the pen or pen point; the rounded or "ball" point being developed into perfect form for smooth writing.

65 In instances where it may be desirable to provide a broad writing tip end of the round or "ball" point type, the blank may have its end squared, as indicated at 21^b in Fig. 8. This type of blank to form the pen or pen point, when subjected to the other operations herein referred 70 to, would result in having the outer corners, indicated at x, slightly rounded by the "wet scouring" or other tumbling operation, and would result in the production of a writing tip somewhat broader than that produced from a blank

having the rounded terminal, such as indicated in Figs. 1, 2, 3, et seq.

It is within the scope of my invention to alter the shape of any of the forms of the recesses hereinbefore referred to, as by tapering them in 5 the manner indicated in Fig. 13, which has the effect of providing a sharper protuberance on the under side of the blank. As a result of such modification, I may produce in the finished pen or pen point a protuberance such as that illustrated in Fig. 17, which provides a finer writing point or surface.

Other forms of pens or pen points may have the ends of the nibs curved transversely or at 15 right angles to the longitudinal axis of the pen or pen point and fragmentary views of blanks from which such pens or pen points may be made are indicated in Figs. 18 and 19, such curved recessing producing a rounding on the under side of the nibs at the writing tip end of 20 the same. Pens or pen points of this type may be produced in a manner precisely similar to that described with respect to steps followed in the production of pens or pen points having a rounded or "ball" point.

By reason of the method of manufacture hereinbefore outlined, which includes the presence in the blank of the gap between the nib portions thereof, all the rough edges of the flat blank have been removed and the corners rounded, and a 30 pen or pen point with a smooth writing tip surface has been developed from the "finished", flat blank; the "wet scouring" or other abrasive treatment of the "blank" in the "flat" cleaning, smoothing, and/or rounding all the rough corners of the "blank" before the pen or pen point is formed or raised therefrom. The "raising" 35 operation transforms the "flat" blank to pen or pen point form and simultaneously brings the spaced nibs into relative contact and proper 40 writing position and sets the nibs in such condition. Except for the polishing step, which does not alter the form of the pen or pen point, the "raising" step is the last step in the formation of the pen or pen point from the original flat 45 blank to complete pen or pen point form.

It will be understood, of course, that various 50 modifications may be made in the above-described embodiment of my invention without departing from the spirit and scope thereof as set forth in the appended claims.

I claim:

1. The method of making pens or pen points which comprises cutting thin sheet metal stock into the form of pen blanks, shaping the end of 55 the blank which subsequently becomes the writing tip end of the pen or pen point by displacing a portion of the body to form a hollow protuberance on the under side of the blank, dividing said end of the blank into nib portions by a cutting operation which removes a portion of the metal of the blank and passes through said displaced protuberance in the longitudinal axis of the blank, finishing the slotted blank while still in the flat by a tumbling operation, and thereafter raising the finished blank to pen or pen point form and bringing the nib ends into proper writing position.

2. The method of making pens or pen points which comprises cutting thin sheet metal stock 70 into the form of pen blanks with rounded ends, forming a hollow protuberance at the rounded end of the blank by displacing a portion of the body within the margin of said rounded end, dividing said end of the blank into nib portions by 75

5 a cutting operation which removes a portion of the metal of the blank and passes through the displaced protuberance in the longitudinal axis of the blank, finishing the slotted blank while still in the flat by a rumbling operation, and thereafter raising the finished blank to pen or pen point form and simultaneously bringing the rounded nib end into proper writing position.

10 3. The method of making pens or pen points which comprises cutting thin sheet metal stock into the form of pen blanks, shaping the end of the blank which subsequently becomes the writing tip end of the pen or pen point by displacing a portion thereof in the form of a hollow protuberance on the underside of the blank, dividing said end of the blank into separate nib portions by a straight cutting operation which removes a portion of the metal of the blank and passes through the displaced protuberance in the longitudinal axis of the blank, finishing the blank in the flat by a wet scouring operation, and thereafter raising the finished blank to pen or pen point form and simultaneously bringing the nib ends together; such action closing the gap between the separated portions of said hollow protuberance and bringing them into proper writing position.

15 4. The method of making pens or pen points which comprises cutting thin sheet metal stock into the form of pen blanks, piercing the blank, shaping one end of the blank by displacing a portion of the body in the form of a hollow protuber-

20 ance on the underside thereof, dividing said end of the blank into separate nib portions by a cutting operation which removes a portion of the metal of the blank and passes through the displaced protuberance in the longitudinal axis of the blank to the pierce hole, finishing the slotted blank while still in the flat by a wet scouring operation, and thereafter raising the finished blank to pen or pen point form and simultaneously bringing the nib ends together; such action closing the gap between the separated portions 25 of said hollow protuberance and bringing the same into writing position.

25 5. The method of making pens or pen points which comprises cutting thin sheet metal stock into the form of pen blanks with rounded ends, shaping the rounded end of the blank which subsequently becomes the writing tip end of the pen or pen point by displacing a portion of the body thereof to form a deep, relatively pointed protuberance on the underside of the blank, dividing said end of the blank into nib portions by a cutting operation which removes a portion of the metal of the blank and passes through the displaced hollow protuberance in the longitudinal axis of the blank, finishing the slotted blank while still in the flat by a rumbling operation, and thereafter raising the finished blank to pen or pen point form and bringing the sections of the pointed protuberance together in writing position.

30 ALBERT G. FROST.
